INVENTOR.

Lewis Barnett

United States Patent Office.

LEWIS BARNETT, OF LEECHBURG, PENNSYLVANIA, ASSIGNOR TO HIMSELF AND JAMES D. BOAL, OF SAME PLACE.

Letters Patent No. 100,490, dated March 8, 1870.

IMPROVED BOOT-LASTER.

The Schedule referred to in these Letters Patent and making part of the same.

To all whom it may concern:

Be it known that I, LEWIS BARNETT, of Leechburg, in the county of Armstrong, and State of Pennsylvania, have invented certain new and useful Improvements in Boot-Lasters; and I do hereby declare that the following is a full, clear, and exact description thereof, reference being had to the accompanying drawings and to the letters of reference marked thereon, which form a part of this specification.

The nature of my invention consists in the construction and use of devices whereby the uppers of boots or shoes may be drawn tightly around the last during the manufacture of boots and shoes.

In the accompanying drawings—

Figure 1 is an elevation of my invention.

Letters of reference denote parts.

A curved bar, A, of suitable material, forms the main body of my device, to each extremity, A¹, of which are hinged, in any suitable manner, and projecting downward therefrom, curved links A², one to each, the lower inside portions of which are serrated, at R. Midway, or thereabouts, A³, of the said links A², are hinged thereto, or pivoted thereto in any suitable manner, other curved links B, of any suitable material, and having their lower parts serrated, to match or mesh with the serrations of the links A².

To the upper portions of these links B are connected, in any suitable manner, rods B', of any suitable construction, projecting upward diagonally therefrom, and connected in any suitable manner, C', to

a cross-brace, C, which lies above said curved bar A, which has slots S through which said rods B' pass, said cross-brace C being provided at or near its center with a hole, having female screw-threads therein, through which passes an ordinary screwed stock, D, having a handle at its upper part, and being firmly confined, in any suitable manner, at its lower part, to the said curved bar A; the whole being so arranged that the leather encircling the last, being placed between the serrated parts R of the links A² and B, by the revolution of the screw D, the links A² and B close together, holding firmly the leather therein; at the same time, and by the same operation, the said links move inwardly, tightening thereby the leather around the last.

Having thus described my invention, What I claim as new, and desire to secure by Letters Patent, is—

The curved bar A, with the links A² and B, rods B', in combination with the cross-bar C and screwed stock D, when constructed, arranged, and operating substantially as and for the purpose described and set forth.

In testimony that I claim the foregoing as my own, I affix my signature in presence of two witnesses.

LEWIS BARNETT.
